MACHINE FOR COMBING FIBROUS MATERIALS

Leonard T. Evans, Indianapolis, Ind.

Application November 15, 1947, Serial No. 786,197

3 Claims. (Cl. 19—127)

1

The present invention relates to a method of combing fibrous materials, such as journal box waste, and to a machine especially designed and constructed to carry out that method. While I am particularly concerned with the renovation of used journal box waste, I am of the opinion that my method and machine are applicable in the preparation of new waste, and in the processing of other fibrous materials.

One step in renovating used journal box waste, after washing with hot clean oil to remove old oil and grease, moisture, and some foreign solids, is to attempt to straighten and loosen the snarled fibrous material to restore its spongy, resilient consistency which is particularly desired in a material used for stuffing railroad journal boxes. So far as I am advised, it is substantially universal practice to shake, pull, and work snarled masses of such material, by hand, and thereafter to subject the worked material to treatment in a tumbling drum to discharge from the loosened mass dirt, lint, metallics and other undesirable foreign matter. Such manual working, obviously results in wide departures from uniformity of consistency, due to variations in the skill and care with which the working is performed, and further is far from satisfactorily effective because of the power required to straighten and loosen such snarled masses. It is the primary object of my invention, then, to provide a method and means for working such masses of material to accomplish the desired loosening, straightening, and breaking, at high speed, with unheard-of effectiveness, and with a relatively high degree of uniformity of result.

The method of the present invention consists essentially, of engaging a mass of tangled, matted fibrous material with a moving comb whose teeth are transversely spaced with respect to the line of movement of the comb, and concurrently engaging the same mass of material with a second moving comb, whose teeth are similarly spaced, but staggered relative to the teeth of the first comb, the second comb being caused to move in the same direction but at a different speed. The result of this process, of course, is that individual strands and groups of strands of the fibrous material being worked are entrained with the more rapidly moving comb, looping about its teeth, and are dragged past and between the teeth of the more slowly moving comb. Some such strands will be broken, while others will be straightened and brought into a common alignment, and the whole mass of material will be loosened, whereby hopelessly matted lumps

and foreign matter will be more readily segregated from the mass during the subsequent tumbling operation. I have found that journal box waste, when treated in accordance with the present process, is more uniform in consistency, and has an improved resilience, as compared with journal box waste treated in accordance with previously known processes.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a side elevation of a machine constructed in accordance with the present invention and designed to carry out the method of the present invention;

Fig. 2 is a more or less diagrammatic view of the comb-carrying assemblies and the driving means therefor;

Fig. 3 is an end elevation, partly in section, taken from the right hand end of Fig. 1;

Fig. 4 is a perspective view of one slat assembly forming a part of one of the combs; and

Fig. 5 is an enlarged fragmental section of a slat assembly.

Referring more particularly to the drawings, it will be seen that I have illustrated a machine comprising a frame 10 providing a suitable mounting for a transverse shaft 11 carrying a plurality of sprockets 12, and further providing a mounting for a spaced, parallel shaft 13 carrying a plurality of sprockets 14. An endless articulated element, indicated generally by the reference numeral 15, is mounted to run upon the sprockets 12 and 14. The element 15 comprises a plurality of articulated chains 16, the number of chains being equal to the number of sprockets on each shaft 11 and 13. In the illustrated embodiment of the invention, I have shown two sprockets on each shaft, and two chains 16 running upon said sprockets. The chains 16 are bridged by a plurality of slats 17, and in the illustrated embodiment of my invention, the slats are placed in closely adjacent relation in a longitudinal series.

Each slat 17 carries a base strip 18, removably secured thereto by means of screws 19, or other suitable fastening means, and each strip 18 is provided with a series of perforations 20, spaced longitudinally of the strip, and therefore transversely of the element 15. Each perforation 20 is

tapered from that side of the strip which is adapted to be pressed against the slat 17 toward the exposed side of the strip; and a pin or tooth 21 is driven through each of said perforations 20. The teeth 21 are tapered, and are so proportioned and designed that the base of each tooth has a driving fit in its associated perforation 20. After the teeth have been assembled with the strip 18, such strip may be secured to a slat 17 by means of the screws 19, or the like, whereafter the teeth 21, of course, will project outwardly from the chains 16. The slats 17 may be welded, or otherwise permanently or removably secured, to corresponding links in the two chains 16.

The frame 10 further provides journal mountings for two additional shafts 22 and 24, the shaft 22 carrying a plurality of sprockets 23 and the shaft 24 carrying a plurality of sprockets 25; and a second endless articulated element, indicated generally by the reference numeral 26, is mounted to run upon the sprockets 23 and 25. The construction of the element 26 is similar to that of the element 15, including chains 27 running upon the sprockets 23 and 25, and bridged by slat assemblies including teeth projections 28. The shaft 22 is positioned above the plane common to the axes of the shafts 11 and 13, and between the vertical planes including said axes but nearer the shaft 11. The shaft 24 is positioned in a plane including the shaft 22 and substantially parallel with the plane common to the shafts 11 and 13, but considerably beyond the vertical plane including the shaft 13. The teeth 28 have a length substantially equal to the length of the teeth 21, and the plane of the shafts 22 and 24 is so spaced from the plane of the shafts 11 and 13 that the teeth 21 and the teeth 28 intersect a common plane, the teeth 28 clearing the strips 18, and the teeth 21 clearing the corresponding strips of the element 26, by a predetermined dimension which will vary between a sixteenth of an inch and a half inch, depending upon an adjustment later to be described, but which I presently believe will preferably be about one-eighth inch. The arrangement of the teeth on the element 26 is staggered relative to the teeth on the element 15, so that, in operation, the teeth 28 will pass between the teeth 21.

Arranged between the shafts 11 and 13 are a shaft 29 carrying a plurality of sprockets 30 engaging the chains 16, and a shaft 31 carrying a plurality of sprockets 32, similarly engaging said chains. The function of the sprockets 30 and 32 is to support the upper run of the element 15 against sagging, thereby holding such upper run positively in the optimum relation to the lower run of the element 26.

The frame 10 provides a mounting for a motor 33 upon the spindle of which is mounted a V-pulley 34 driving, through a belt 35, a V-pulley 36 on the input shaft 37 of a reduction gear unit 38, whose output spindle carries a pinion 39. The pinion 39 meshes with a large gear 40 carried on the shaft 13; and said gear meshes with an idler gear 41 which, in turn, meshes with a second idler gear 42 driving a small gear 43 on the shaft 24. The gear 42 is mounted on a shaft 44, suitably journalled in the frame, and said shaft carries a sprocket 45 driving, through a chain 46, a sprocket 47 on a shaft 48 carrying a roll 49; and a conveyor belt 50 runs over said roll 49 and over another roll 51 suitably journalled in the frame. The belt 50 is thus positioned below the discharge end of the element 15 to receive material discharged therefrom. The operation of

the conveyor 50 is such as to deliver material deposited thereon to a second conveyor belt 52 running over a roll 53 journalled on the frame 10, and over another roll (not shown) disposed at such a position as to discharge material to another station for further treatment.

The shaft 11 is journalled in movable blocks 54 guided in trackways 56 and adjustable toward and away from the axis of the shaft 13 by means of screws 55. Similarly, the shaft 22 is mounted in blocks 57 slidably guided in trackways 58 and adjustable toward and away from the axis of the shaft 24 by means of screws 59. The function of this type of mounting for the shafts 11 and 22, of course, is to permit adjustment of the tension upon the articulated members 16 and 27.

Adjustment of the clearance between the fingers or teeth of each element and the base strips of the other element can be accomplished by shimming the trackways 58 relative to the frame 10.

In operation, the motor 33 is energized to drive the gear 40 in a counter-clockwise direction as viewed in Fig. 1. The upper run of the element 15 will thus be driven toward the left, as viewed in Fig. 2. Counter-clockwise motion of the gear 40 will result in clockwise rotation of the gear 43 to drive the lower run of the element 26 toward the left as viewed in Fig. 2; but, because of the difference in pitch diameter between the gear 40 and the gear 43, the lineal velocity of the element 26 will exceed that of the element 15. Preferably, the ratio between the gear 40 and the gear 43 will be such as to cause the speed of the element 26 to exceed the speed of the element 15 in the ratio of 3.6 to 1. I have found that, for optimum results, the lineal velocity of the element 26 should be within the range between 69 feet per minute and 75 feet per minute. Under these conditions, of course, the element 15 will run within the range between 16 2/3 feet per minute and 20.3 feet per minute. The strand characteristics of journal box waste will vary; and the longer the average strand of the material being worked, the slower should be the speed of the elements 26 and 15. It is my present opinion that, in a machine such as I have here illustrated, which includes no means for readily varying the speed of the comb elements, optimum results will be obtained by operating the element 26 at a lineal velocity of approximately 69 feet per minute. While that speed is not perfect for all batches of waste fed through the machine, it will give good results on waste batches of varying characteristics.

In a waste renovating plant, used journal box waste will be passed through standard cleaning operations, and then will be fed to the illustrated machine, through the hopper 60. The hopper is preferably constructed with a relatively shallow mouth having a width corresponding to the width of the elements 15 and 26. The material is discharged from the hopper onto that portion of the element 15 over which the element 26 does not hang, and is engaged, at a plurality of points in a line transverse to the line of movement, by the teeth 21. Thus, the material is carried into the region overhung by the element 26. As the material comes into that region, it is engaged, at a plurality of points spaced transversely of its line of movement, by the teeth 28. Since the teeth 28 are moving somewhat more rapidly than are the teeth 21 they exert a combing action upon the waste, dragging engaged portions thereof between

the more slowly moving teeth 21 to straighten, loosen, and align the elements of the mass of material. As the material begins to pass around the sprockets 14, the teeth 28 exert upon it a force tending to disengage it from the teeth 21; and, as the teeth 21 pass around the sprockets 14, the material drops therefrom onto the conveyor 50, which delivers it to the conveyor 52, which carries the material to the next station in the renovating process.

I claim as my invention:

1. A machine for combing fibrous materials such as journal box waste, comprising a pair of spaced rotors, an endless element mounted to run upon said rotors and provided with a plurality of outstanding fingers, a second pair of spaced rotors, a second endless element mounted to run upon said second pair of rotors and provided with a plurality of outstanding fingers, the lower run of said second element being positioned in adjacent parallelism with the upper run of said first element with the fingers of said adjacent runs in interdigitating relation, and means for driving said rotors to move said adjacent runs in a common direction at different speeds, each of said elements comprising a plurality of endless articulated members and one of each pair of rotors having driving connection with its associated articulated members, the articulated members of each element being bridged by a plurality of transversely-disposed slats arranged in a longitudinally-spaced series, said fingers being carried upon said slats in a transversely spaced series on each slat, a base strip for each slat, and means removably securing each base strip to its slat, each base strip being provided with a transversely-spaced series of perforations tapering toward the exposed side of said strip, and said fingers comprising tapered pegs driven into said perforations from the side of said strip abutting its slat.

2. A machine for combing fibrous materials such as journal box waste comprising a pair of spaced rotors, an endless element mounted to run upon said rotors and provided with a plurality of outstanding, blunt-edged pulling fingers, a second pair of spaced rotors, a second endless element mounted to run upon said second pair of

rotors and provided with a plurality of similar outstanding fingers, the lower run of said second element being positioned in adjacent parallelism with the upper run of said first element with the fingers of said adjacent runs in interdigitating relation, and means for driving said rotors to move the adjacent runs in a common direction at different speeds, the speed of said second element exceeding the speed of said first element in a ratio of approximately 3.6 to 1, and the speed of said second element being within the range between sixty feet per minute and seventy-five feet per minute.

3. A machine for combing fibrous materials such as journal box waste comprising a toothed element, means for moving said element, at a velocity between 16 $\frac{2}{3}$ feet per minute and 20.8 feet per minute, from a material-receiving station toward a material-discharge station, the teeth of said element being arranged in a series spaced transversely of the line of movement of said element, a second toothed element, and means for moving said second element, at a velocity between 60 feet per minute and 75 feet per minute, in the direction of movement of said first-named element, the teeth of said second element being arranged in a series spaced transversely of said line of movement and staggered relative to the teeth of said first-named element, said teeth of both said elements intersecting a common plane.
